UNITED STATES PATENT OFFICE.

THOMAS SMITH, OF BROOKLYN, ASSIGNOR TO MAX BROMBACHER, OF NEW YORK, N. Y.

MACHINE FOR FOLDING SHEET METAL.

SPECIFICATION forming part of Letters Patent No. 586,159, dated March 19, 1895.

Application filed March 28, 1894. Serial No. 505,603. (No model.)

To all whom it may concern:

Be it known that I, THOMAS SMITH, of the city of Brooklyn, in the county of Kings and State of New York, have invented a certain 5 new and useful Improvement in Machines for Folding Sheet Metal, of which the following is a specification.

My improvement relates to machines for folding the edges of sheet metal.

10 I will describe a machine embodying my improvement and then point out the novel features in the claims.

In the accompanying drawings, Figure 1 is a top view or plan of a machine embodying my 15 improvement, certain portions being broken away and one part being swung up out of its normal position. Fig. 2 is a side view of the machine. Fig. 3 is a central transverse section. Fig. 4 is a similar view of certain parts, in another position. Fig. 5 is a transverse section 20 taken on the plane of the dotted line 5, Fig. 1. Fig. 6 is a back view of the machine.

Similar letters of reference designate corresponding parts in all the figures.

25 In general construction this machine is substantially like the machine which is set forth in United States Letters Patent No. 351,490, granted October 6, 1886, to Charles Brombacher.

30 A designates a folding bar provided with journals A' supported in bearings provided in a swinging frame b and provided with an arm B, whereby it may be oscillated.

C designates a plate, around whose edge 35 the bar A is oscillated. Under it is a clamp R consisting of a portion of the frame b. A gage D is employed to determine the width of the portion of metal which is bent or folded over and this gage is located below the plate C, the latter being secured above it by means of screws c otherwise.

The metal to be bent is introduced between the plate C and the folding bar A, it being slipped into the space between the same as far 45 as permitted by the front edge of the gage D.

The journal A' of the folding bar may be provided with rollers a' which may be made integral. The rollers a' rest upon rollers e having their journals supported by bearings 50 in a frame F, which is pivotally connected at one end to standards g extending upwardly

from the base-plate G of the machine. To these standards g the frame b is also pivotally connected. The outer end of the frame F is supported by means of screws g' which extend 55 through tapped holes in the frame F and bear upon the base plate G. By turning the screws different adjustments of the frame F may be made to suit different thicknesses of metal.

The rollers a' of the folding bar A have at 60 a certain point in their circumferences, a notch a², corresponding in contour with the circumference of the rollers e these notches being immediately above the rollers e when the folding bar is extended out horizontally 65 and being removed out of contact with the rollers e when the folding bar is swung upwardly, so as to cause the frame b to be swung upwardly. Thus the clamp R is moved upwardly to clamp the edge of the metal under 70 the plate C.

It will be understood that the frame b is supported at all times by the frame F because these rollers a' rest upon the rollers e whose journals are sustained by the frame F.

75 It will be seen that the folding bar is composed of two parts, one of which consists of a bar a³ having formed integral with it the rollers a' and journals A' and a second part made in the form of a plate a⁴, provided with 80 lugs a⁵ which are pivotally connected to lugs a⁶ formed integral with the bar a³ by studs a. Thus a pivotal connection is provided between the plate like part a⁴ of the folding bar and the bar like part a³ of said folding bar.

85 It will be seen, especially by reference to Figs. 3 and 4 that the plate like part a⁴ of the folding bar is provided with flanges that extend transversely so that when the plate like part a⁴ of the folding bar is in its normal position, these flanges are extended on opposite sides of the bar like part a³ of the folding bar. One of the flanges a⁷ is provided with a series 90 of inclines a⁸. With these inclines coact inclines v formed on a bar V that is fitted to slide on the bar a³ of the folding bar, so as to be capable of moving longitudinally under the inclines a⁸. A rod or stud v' extends from the bar V through a slot formed longitudinally in the bar like part a³ of the folding bar 95 and is connected with one arm of a lever V'. As here shown the stud is screw-threaded

on the end and fitted with a clamping nut so that by turning the nut one of the arms of the lever may be clamped between the nut and the adjacent surface of the bar like part 5 a^3 of the folding bar. Thus it will be seen that the bar V may be shifted into different positions and fastened after adjustment. The inclines v do not by a longitudinal movement of the bar V coact with the inclines a^8 to raise 10 the plate like part a^4 of the folding bar, but the bar V is shifted merely to throw different parts of its inclines v opposite the inclines a^8 .

When the folding bar is in its normal position, as shown in Figs. 2 and 3, its plate like 15 part a^4 will rest upon the pins a^9 extending upwardly from the frame F. While so supported that surface of the plate like portion a^4 which will be uppermost will be substantially on a level with the top surface of the 20 clamp R. Thus facility is afforded for feeding a strip or sheet of tin into position.

When the folding bar is oscillated, the plate like part a^4 will leave the pins a^9 , the inclines a^8 coming in contact with the inclines 25 v . The plate like part a^4 will by this means rest upon the bar like part a^3 . On further movement of the folding bar, the plate like part a^4 is carried around and acts upon the sheet of metal. The adjustment of the bar 30 V determines the amount of oscillation which shall be given to the plate like part a^4 of the folding bar independently of the bar like part a^3 .

As soon as the folding bar is oscillated and 35 the clamp R thereby raised, the plate like portion a^4 of the folding bar will be left behind, so that it will no longer be upon a level with the top of the clamp, as illustrated in Fig. 4. The position of the plate like portion 40 a^4 will after the beginning of the oscillation of the folding bar be determined by the inclines a^8 in connection with the inclines v . Hence by adjusting the bar V, the sharpness or bluntness of the bend which may be made 45 in a strip or sheet can be determined.

U^1 , U^2 designate two stops pivoted to a lug u extending from the frame b and capable of being swung, one at a time, into position opposite one of the lugs a^6 to limit the oscillating movement of the folding bar. Both may be swung out of the way if desired. Either may be used to secure a definite position of the folding bar at the end of its oscillation.

G' designates an upward extension from the 55 base piece G, and serving to support the plate C, around the edge of which the folding bar moves. This support G' is provided at about the middle of its length with an extension G^2 . The gage D has an extension d , that fits in 60 to a passageway in the extension G^2 of the support G' . This passageway is shown as being provided with side flanges r , r' , between which the extension d of the gage slides. Portions of the inner bearing surfaces of flanges r , r' are shown as being cut away forming spaces r^2 , r^3 . The gage is 65 adjustable back and forth in the direction of

the length of its extension d , and is guided by the latter in its movements. The extension G^2 may be provided with a spring g^2 , 70 here shown as made in the form of a plate having a bearing at its middle against the extension d of the gage and two bearings near its ends against the inside of the extension G^2 . A screw g^5 working in a tapped hole 75 in the side of the extension G^2 bears against the middle portion of the spring and serves, by exerting pressure upon the same, to steady the extension d of the gage in its longitudinal movement. At the top of one side portion 80 of the extension d is an index scale d' , which in connection with the edge of the extension G^2 will indicate the position of the gage. In the extension G^2 beneath the extension d of the gage is a spring D' . Its middle portion 85 rests in a groove formed in the extension G^2 and its ends against the under surface of the side portions of the extension d . By means of this spring the gage is held upward against the plate C, which is of importance. 90

I designate a lever fulcrumed to the under side of the extension G^2 by means of a pin, i . At the inner end it is pivotally connected to a link J, that is pivotally connected to the gage D and works in the space formed in the 95 interior of the extension d of the gage. By oscillating the lever I, by manipulating its outer end with the hand, the gage may be moved backward or forward. The lever I is provided with a slot, i' , which is arc shaped 100 and concentric with its fulcrum - pin i . A screw I' , which is fastened into the extension G^2 , extends through the slot i' of the lever. A nut, I^2 , applied to the outer end of the screw below the lever, serves to secure the lever, 105 and consequently the gage, in position after adjustment. It in effect constitutes, with the screw and the lever, a lock for the gage.

What I claim as my invention, and desire to secure by Letters Patent, is— 110

1. In a machine for folding sheet metal, the combination with a plate around the edge of which the sheet metal is to be folded, of a folding bar comprising a plate like part and a bar like part having a pivotal connection with 115 each other, supports independent of the bar like part of the folding bar for supporting the free end of the plate like part, and means carried by the folding bar for varying the position of the plate like part of the folding bar, 120 substantially as specified.

2. In a machine for folding sheet metal, the combination with a plate around the edge of which the sheet metal is to be folded, of a folding bar comprising a plate like part and a 125 bar like part having a pivotal connection with each other, supports independent of the bar like part of the folding bar for supporting the free end of the plate like part, inclines on the plate like part, and means, consisting of a sliding bar having inclines, carried by the folding bar for varying the position of the said independently movable plate like part of the folding bar, substantially as specified. 130

3. In a machine for folding sheet metal, the combination with a plate around the edge of which the sheet metal is to be folded, of a folding bar comprising a plate like part and a 5 bar like part having a pivotal connection with each other, supports independent of the bar like part of the folding bar for supporting the free end of the plate like part, inclines on the plate like part, means, consisting of a sliding 10 bar having inclines, carried by the folding bar for varying the position of the said independently movable plate like part of the folding bar, a slot in the main part of the folding bar, a stud passing from the sliding bar through said slot, a lever connected with said stud for adjusting the sliding bar and a clamp 15 acting upon the said lever to secure the bar in position, substantially as specified.

4. In a machine for folding sheet metal, the 20 combination of a folding bar and a number of independently movable pivoted stops against which the bar rests in its abnormal or folding position, substantially as specified.

5. In a machine for folding sheet metal, the 25 combination with a plate around the edge of

which the sheet metal is to be folded, a folding bar, a clamp, and a gage extending under said plate, of a spring inserted under said gage for pressing the same up against the said plate, substantially as specified. 30

6. In a machine for folding sheet metal, the combination with a plate around the edge of which the sheet metal is to be folded, a folding bar, a support provided with an extension, a clamp, and a gage having an extension, of 35 a spring, consisting of a strip of metal, inserted between the extension of said support and the extension of the gage and a screw engaging with the extension of said support and bearing against said spring, for holding 40 the gage securely in position, substantially as specified.

In testimony whereof I have signed my name to this specification in the presence of two subscribing witnesses.

THOMAS SMITH.
